DESIGN FOR A JACKET OR SIMILAR ARTICLE

Jacob Cohen, New York, N. Y.

Application July 21, 1938, Serial No. 78,631

Term of patent 3½ years

To all whom it may concern:

Be it known that I, Jacob Cohen, a citizen of the United States, and resident of New York city, in the county of New York and State of New York, have invented a new, original, and ornamental Design for a Jacket or Similar Article, of which the following is a specification, reference being had to the accompanying drawing, forming a part thereof.

Fig. 1 is a front elevational view of a jacket or similar article, showing my new design.

Fig. 2 is a rear elevational view of Fig. 1.

Fig. 3 is a view similar to Fig. 1, but illustrating the jacket in an open position.

Fig. 4 is a side elevational view of the jacket.

The characteristic feature of my design resides in the combination on the jacket disclosed of the specific floral elements as shown.

I claim:

The ornamental design for a jacket or similar article, as shown and described.

JACOB COHEN.
